UNITED STATES PATENT OFFICE

2,184,502

WIRES ROPE CENTER

Frank R. Metcalf, Auburn, N. Y., assignor to
Columbian Rope Company, Auburn, N. Y., a
corporation of New York

Application May 6, 1938, Serial No. 206,450

3 Claims. (Cl. 57—153)

This invention relates to improvements in wire ropes and, particularly, to wire rope centers.

Primarily, the object of the invention is to provide a wire rope center better adapted to support the strands of the wire rope, in that the crevices between the wires of the strand will be more completely filled by the center.

Another object is to provide a wire rope center having a substantially smooth surface free of irregularities or undulations. In present-day practice, multi-strand rope of comparatively small cross-section is commonly used for wire rope centers and the spirally extending indentations formed in the surface of the rope by the spiral disposition of the several strands interfere with or prevents proper positioning or supporting of the strands on the center, by reason of the fact that the center does not properly fill the crevices between the wires of the individual strands of the wire rope. With the present invention, these difficulties are eliminated by reason of the fact that the surface of the present center is free of the spirally extending indentations or other irregularities.

A still further object of the invention is to provide a wire rope center in which the lubricant for the fibres of the strands of the center will be retained therein, this preferably being accomplished by the use of a material for filling the indentations in the surface of the center that is capable of functioning as a seal for retaining the lubricant in the center strands.

With these and other objects in view, the invention consists in certain details of construction and combinations and arrangements of parts, all as will hereinafter be more fully described and the novel features thereof particularly pointed out in the appended claims.

In the accompanying drawing—

Fig. 1 is a perspective view of a section of a wire strand cable with the wire strands slightly opened up;

Fig. 2 is a detail view of a length of the center with one end thereof opened up; and

Fig. 3 is a transverse sectional view of the center.

The present invention is shown in connection with the usual wire rope construction, the same comprising a plurality of wire strands 10 laid spirally on the center or core C. The preferred form of center illustrated in the present instance is composed of a plurality of strands 11. The strands which may be of vegetable fibres are, of course, formed of a multiplicity of spun yarns 55 and the several strands are twisted together in

accordance with ordinary practice, so that there is formed on the surface of the center a plurality of spirally disposed indentations 12, sometimes referred to as contlines. In present-day wire strand rope manufacture, where ropes of small 5 cross-section are used and have these spiral indentations in the surface thereof, the presence of these indentations interferes with the proper seating or positioning of the wire strands on the core or center, due to the fact that the irregularities in the cross-section of the center prevent the crevices in the individual wire strands being uniformly and completely filled by the fibrous body formed by the center.

In accordance with the present invention, these 15 difficulties are eliminated by filling the indentations with a plastic material, preferably a cellulose base material or, if desired, synthetic plastic materials or solutions of the same may be used for this purpose. For reasons which will later 20 appear, it is preferred to at least slightly coat the entire surface of the stranded fibre core. The body of material constituting this filler for the irregularities in the surface of the fibre core and the coating of the center is indicated at 13 25 and, as is more clearly seen in Fig. 3, the result is the production of a center of substantially circular cross-section so that, when the wire strands of the rope are laid on the center, the crevices in the surface of the individual strands of the 30 rope at the points where they contact the surface of the center will be uniformly filled. It is, of course, understood that the wire strands of the rope carry the tensile stresses, but upon being wound on the center, impose compressive strains 35 on the center, to the extent that the wire strands are embedded in the center to at least partially fill the valleys or spiral depressions formed by the surfaces of contiguous wire strands. However, with a center such as the present, having 40 a truly cylindrical surface formed of material moldable in the sense that it can flow, so to speak, into the crevices in the surfaces of the wire strands when placed under compression by those strands, the several strands will naturally 45 be uniformly supported at all points on the surface of the center.

It is also important that the strands of wire 50 rope centers, or rather the fibres of which the center is formed, be properly and adequately lubricated and, as a rule, the desired quantity of lubricant is incorporated in the same during the production thereof. This is true, whether the center is of strand formation or formed of a single body of vegetable fibres, as distinguished 55

from a multi-strand construction. With this thought in mind, the filler material 13 should also be capable of functioning as a seal for retaining the lubricant in the core or center. The 5 material 13, therefore, serves a dual function, in that it insures uniform support for the wire strands of the rope or cable and, in addition, efficiently seals the fiber center to prevent loss of lubricant.

10 As just indicated, it will be appreciated that the center need not be of multi-strand construction, but might well be a large, single body of fibres which may be termed, for the purposes of the present invention, a single strand, although, 15 in the rope industry, it would probably be more properly referred to as a sliver of fibres made up into a center. It will also be appreciated that the present invention is not necessarily limited to use in connection with centers or cores 20 made of spun fibres, as the use of paper in the production of centers is also possible, as indicated in Patent No. 1,916,135. It is also to be understood that the invention is not limited to a filler material capable of functioning as a seal 25 for the lubricant in the center, as it is entirely possible that this feature might be omitted in the sense that the filler material will function solely to eliminate irregularities in the surface and cross-section of the finished center.

30 One mode of carrying out the present invention comprises passing the core or center, whether it be of single or multi-strand construction, through a bath of fluid or plastic material of cellulosic base that will penetrate, to some 35 extent, the outside surfaces of the fibres constituting the center, after which the center is passed through a bath of cellulose base materials, or a compound of such materials, whereby a coating is applied to the core. The interstices 40 or valleys formed by the strands of the core, or other irregularities in the surface thereof, will be filled with this filler material, which blends with the core by means of cohesion between the

cellulose materials and the exterior of the rope structure. After passing through such a bath, the coated core is passed through a die to wipe off surplus cellulose materials and thence through proper drying and conditioning equipment. 5 These steps may be repeated, depending upon the amount of coating material applied by each immersion of the core in the bath, the principal point being that sufficient coating material is applied to produce a core of circular cross-section and, preferably, to entirely coat the surface so as to seal the lubricant in the core.

10 As to the filler materials used, cellulose ethers and esters, such as ethyl cellulose, cellulose nitrate and cellulose acetate are, at present, believed to be preferred.

15 What I claim is:

1. A center for wire ropes comprising a plurality of groups of fibres twisted together forming a body having depressions extending spirally 20 of its surface, a lubricant incorporated in said body, and sealing material substantially covering said body and capable of retaining the lubricant therein, said sealing material also filling said depressions to impart an even surface substantially free of undulations to the center.

2. A center for wire ropes comprising a plurality of groups of fibres twisted together forming a body having depressions extending spirally 30 of the body, a cellulose base material filling said depressions, and a lubricant incorporated in said fibre body, said filler material sealing said lubricant in said body and imparting to said body an even surface free of undulations.

3. A center for wire ropes comprising a plurality of fibres associated to form an elongated body, said body having depressions or irregularities in its exterior surface, and a cellulose base material filling said depressions or irregularities to impart to said body an even surface free of 35 undulations.
